CLAIM

The ornamental design for a book light, as shown and described.

DESCRIPTION

FIG. 1 is a front perspective view of a book light, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged detail view of area 9 in FIG. 1 thereof;

FIG. 10 is an enlarged detail view of area 10 in FIG. 3 thereof;

FIG. 11 shows a perspective view of the book light in a position of use; and,

FIG. 12 shows a perspective view of the book light in another position of use.

The broken lines in the drawings illustrate the portions of the book light, which form no part of the claimed design.

The dash-dot-dash broken lines encircling the enlarged views are for annotative purposes only and form no part of the claim thereof.
